UNITED STATES PATENT OFFICE.

JOHN R. DONNELLY, OF FAIRFIELD, MAINE, ASSIGNOR OF ONE-HALF TO DANIEL B. DONNELLY, OF FAIRFIELD, MAINE.

ATTACHMENT FOR OIL-STOVES.

1,366,365.

Specification of Letters Patent. Patented Jan. 25, 1921.

Application filed August 18, 1919. Serial No. 318,109.

To all whom it may concern:

Be it known that I, JOHN R. DONNELLY, a citizen of the United States, residing at Fairfield, in the county of Somerset and 5 State of Maine, have invented certain new and useful Improvements in Attachments for Oil-Stoves, of which the following is a specification.

My invention relates to a shield for oil 10 stoves of that type making use of a vertical chimney, located beneath a circular grate upon which is placed the oven or vessel to be heated. The invention is particularly adapted to the so-called "blue flame" oil 15 stove such as the "Perfection" now so common on the market.

The grate and the top of the chimney in the ordinary commercial oil stove are separated by a considerable space, which allows 20 free access of the outside air and which has a very considerable cooling effect upon the vessel which is being heated.

The diameter of the opening at the top 25 of the chimney is very much less than the diameter of the grate and the heat arising from the chimney is concentrated more or less within a limited space and is not properly distributed over the bottom of the vessel or other article to be heated.

30 The object of my invention is, first, to prevent the free access of the outside air to the space beneath the vessel and, secondly, to effect the even distribution of the heated air and gases arising from the chimney of the stove, whereby the heating effect of the stove is greatly accentuated.

In carrying out my invention, I interpose 35 between the grate and the top of the chimney an annular shield which is preferably made with an upwardly flaring formation, the outer diameter of said shield being substantially that of the grate or stove opening and the inner diameter being slightly greater than that of the chimney opening.

45 This construction is made more effective by uniting with it a flanged or flaring guard surrounding the top of the chimney and separated from the shield by an annular vent or air opening.

50 This attachment is preferably formed to fit the ordinary commercial "blue flame" stove and results in the increased efficiency of such stoves.

I have illustrated in the accompanying

drawing an attachment constructed according to my invention, applied to the ordinary "Perfection oil stove," so called. 55

In the drawing:

Figure 1 is a section on the line 1—1 of Fig. 2, and 60

Fig. 2 is a plan of the device.

2 represents the flat top of the oil stove containing the opening 3, 4 is the chimney having the contracted opening 5, and 6 is the grate upon which is placed the article to be 65 heated.

These parts are all common to the commercial oil stove and form no part of my invention. The shield 7 is preferably an annular casting, the outer diameter being 70 substantially that of the grate so that it rests upon the edge of the stove opening 3 and the upper portion is hollowed out so that the grate 6 rests on it in the same relative position as it rests on the stove opening. 75

The inner diameter of the shield 7 is slightly larger than the opening 5 in the top of the chimney and the shield is made with an upwardly flaring form which is slightly curved, or cup shaped, leaving a 80 flat, slightly tapering space beneath the grate.

The chimney is protected from currents of air by a cylindrical guard 8 having at its upper edge an outwardly extending flange 9. 85

The guard 8 fits closely around the upper end of the chimney, extending somewhat above the same and it is suspended from the shield 7 by hangers 10, which are preferably formed integral with the casting 7 and secured by suitable bolts 11 to the inner surface of the guard 8. 90

The effect of this attachment is to spread and evenly distribute the column of heated air and gases which rise through the opening 5 and also to protect the bottom of the grate and any vessel or article placed thereon to be heated, from the inrush of cold air which would otherwise mingle with the ascending column of heated air and gas. 95

The upper end of the chimney is also protected from the effect of lateral drafts of air which would otherwise have a disturbing effect upon the action of the burner. 100

The annular space allows a limited 105 amount of fresh air to enter when the grate is unobstructed or partially so. When the grate is wholly covered, however, and the

upward flow of hot gases is checked or smothered, this annular space furnishes a vent by which the excess gases flow off around the sides of the burner and relieves 5 any back pressure within the chimney.

An attachment constructed as above described has the effect of making the oil stove far more efficient than when used without it, by concentrating the heat, distributing the 10 same, and by preventing the cooling effect of the exterior air.

I claim:

1. An oil stove having a chimney, a grate above said chimney, an upwardly spreading 15 annular shield interposed between the grate and chimney adjacent to the grate and an annular guard surrounding the top of the chimney, its upper edge being of greater diameter than the lower edge of said shield 20 and spaced from said shield to form an annular upwardly and outwardly extending venting space.

2. An oil stove having a chimney, a grate above said chimney, an upwardly spreading 25 annular shield interposed between the grate and chimney adjacent to the grate and an annular guard suspended from said grate surrounding the top of the chimney, its upper edge being of greater diameter than 30 the lower edge of said shield and spaced from said shield to form an annular up-

wardly and outwardly extending venting space.

3. An oil stove having a chimney, a grate above said chimney, an upwardly flaring 35 annular shield interposed between the grate and chimney adjacent to the grate, an annular guard surrounding the top of the chimney spaced from said shield to form an upwardly and outwardly flaring venting space. 40

4. An oil stove having a grate opening, an annular shield fitting in said opening, a grate fitting in said shield, a chimney, an annular chimney guard suspended from said shield and fitting over the upper end of said 45 chimney, leaving an upwardly and outwardly flaring venting space between said guard and shield.

5. An oil stove having a grate opening, an upwardly flaring annular shield fitting 50 in said opening, a grate above said shield, a chimney, a chimney guard having an annular flange suspended from said shield and fitting over the upper end of said chimney leaving an upwardly and outwardly flaring 55 venting space between said shield and guard.

In testimony whereof I have affixed my signature, in presence of two witnesses.

JOHN R. DONNELLY.
